United States Patent Office

Des. 179,567

Patented Jan. 22, 1957

179,567

COMBINED FIGURINE AND PAPER WEIGHT

John Norris Hall, Atlanta, Ga.

Application April 2, 1956, Serial No. 40,877

Term of patent 14 years

(Cl. D29—23)

Fig. 1.

Fig. 2.

Fig. 3.

Fig. 1 is a side perspective view of a combined figurine and paper weight, showing my new design;

Fig. 2 is a top plan view thereof; and

Fig. 3 is a front elevational view thereof.

I claim:

The ornamental design for a combined figurine and paper weight, as shown.
